UNITED STATES PATENT OFFICE

1,969,412

SAFE DEVICE

William C. Miller, Canton, Ohio, assignor to Diebold Safe & Lock Company, a corporation of Ohio

Application June 6, 1932, Serial No. 615,700

11 Claims. (Cl. 109—1)

The invention relates to safe devices and particularly to money-chests, or the like, in which the daily receipts of stores, etc., may be placed for temporary safe keeping.

5 A safe or money-chest of this type is shown in my co-pending application, S. N. 511,893 filed Jan. 28, 1931.

10 A device embodying one form of the present invention comprises a block of concrete which is sufficiently heavy that it cannot be removed readily from the premises in which it is installed. Embedded in the concrete block is a heavy-walled container which is preferably formed from cast steel, the container being provided with a round 15 door-opening which is normally closed by a closure-member provided with a lock of the type that must be manipulated by two keys when it is to be locked or unlocked. A slot extends from the door-opening through the wall of the container into the interior thereof. The closure-member is of such conformation that when it occupies one position in the door-opening, the outer end of the slot is not closed thereby and one may deposit money in the container through 20 the slot. The closure-member may be angularly displaced in the door opening from the position described above to a position wherein it closes the outer end of the slot. The construction of the lock is such that it may be manipulated to hold 25 the closure member locked to the container while it is in either of these positions and while it is being displaced from one to the other. The lock may also be manipulated to lock the closure-member against angular displacement when it is 30 in the position wherein it covers the outer end of the slot. Both keys must be employed to adjust the lock to unlock the closure-member entirely from the container so that it may be lifted bodily therefrom. In practice, one key is retained on the premises and the other key is in the possession of some agency which collects the funds deposited in the container at frequent intervals. The key kept on the premises is adapted to manipulate the lock to such an extent that 35 the closure-member may be angularly displaced to cover or uncover the slot, but if access is to be had to the container to remove the contents thereof, both keys must be employed.

40 In the preferred embodiment of the invention, the lock controls a bolt which is engageable with a recess and an arcuate slot provided in the wall of the container. Improved means operatively connecting the bolt and the lock insures that the bolt will remain in its locking position if an attempt is made to gain access to the container by

driving the lock from the closure member. The lock may be driven from the closure-member by hammering on it with suitable tools through the key-holes provided in the closure member.

45 Other advantages will become apparent as the following detailed description progresses, reference being had to the accompanying drawings, wherein:

Figure 1 is a vertical section taken through a device which embodies the invention, the money-chest proper being shown in elevation.

Figure 2 is a fragmentary plan view of the improved device.

Figure 3 is a section taken on line 3—3 of Fig. 4.

Figure 4 is an enlarged section taken on line 4—4 of Fig. 2.

Figure 5 is a section taken on line 5—5 of Fig. 2, the closure member for the money-chest being shown in a position wherein it closes a money-chest, and

Figure 6 is a section taken on line 6—6 of Fig. 5.

50 In the drawings, A designates a block of concrete; B, a sheet metal shell housing the block A; C, a money-chest; and D, a door or closure-member for the money-chest.

55 The concrete block A is of such proportions that it cannot be removed readily from the store, or the like, in which it is placed. The block may be formed in the shell B at the store, or the like, or the entire device may be completely fabricated before it is shipped by the manufacturer.

The money-chest C is embedded in the concrete block A with its opening at the top thereof, the money-chest is of such conformation that it becomes anchored in the block.

60 As best shown in Fig. 4, the money-chest C comprises a heavy walled container 10 which is preferably formed from cast steel. An annular flange 11 formed at the upper end of the container 10 rests upon the top wall of the shell B.

The container 10 is provided with a door-opening 12 for the door or closure-member D and a money-slot 13 formed in the wall of the container 10 leads from the door-opening 12 to the interior of the container. It will be readily understood that when the door D is in the position

65 wherein it is shown in Fig. 4, one may deposit money in the container 10 by dropping it through the slot 13. When the door D is turned at right angles to the position wherein it is shown in Fig. 4 so that it occupies the position wherein it is shown in Fig. 5, the door E closes the outer end 70 of the money-slot 13.

105

110

The closure-member D preferably comprises a heavy body portion 15 of cast steel. The top surface of the body portion 15 is beveled or inclined as at 16 so that the outer end of the slot 13 is accessible when the closure member D is in the position wherein it is shown in Fig. 4. It will be noted that the body portion 15 is provided with a shoulder 17 which rests upon diametrically disposed lugs 18 formed integral with the container 10. This construction permits one to angularly displace the closure member D around the vertical axis of the container 10 while it rides upon the lugs 18. The purpose of this construction will presently appear.

Secured to the bottom surface of the body portion 15 is a lock 20 which comprises a bolt 21. (See Figs. 3 and 6.) Pivoted to the bolt 21 by a pin 23 is an arm 24 of a bell crank lever 25 which comprises an arm 26 pivoted to a link 27 by a pin 28. The bell crank lever 25 is pivoted to the body portion 15 by a pin 30. The link 27 is pivotally connected to a bolt 32 by a pin 33. The bolt 32 is slidably journaled in a door 34 formed in the body portion 15 and is adapted to enter a recess 35 formed in a hardened steel plug 36 which is seated in a bore 37 formed in the container 10.

The bolt 32 is provided with a bore 40 in which a plug 41 is slidably journaled. It will be noted that the pin 33 projects into a recess 44 formed in the plug 41. Disposed in the bore 40 and interposed between the bottom thereof and the plug 41 is a compression spring 45 which yieldingly urges the bolt 32 and the plug 41 in opposite directions. The construction is such that if the lock 20 is driven off of the bottom face or surface of the body portion 15, the link 27 will be driven downwardly so that the pin 33 will be withdrawn from the bolt 32 and the plug 41. The compression spring 45 will then expand so that the forward end of the bolt 32 will remain in the recess 35 and the plug 41 will be driven back against the bottom surface of the bore 34. Obviously, the closure member D will remain locked to the container 10.

The hardened steel plug 36 prevents unauthorized persons from gaining access to the contents of the container 10 by drilling through the wall of the container at this point so that the bolt 32 can be driven back into the bore 34. It will be noted that the plug 36 is provided with an annular shoulder which seats upon an annular shoulder 50 provided in the bore 37. The outer end of the bore 37 is filled by a steel plug 52 which is welded to the container 10.

The lock 20 and the mechanism which operatively connects it to the bolt 41 are disposed in a recess 55 formed at the bottom of the body portion 10, the recess 55 being preferably covered by a plate 56 which is secured to the body portion 15 by screws 57.

As best shown in Figures 3, 5 and 6, the body portion 15 is provided with integral lugs 60 adapted to pass between the lugs 18 when the closure member D is lifted out of the door opening 12. When the closure member D is to be returned to the door opening 12, the closure member D is locked into the opening in such manner that the lugs 60 drop down between the lugs 18 and the shoulder 17 on the body member 15 comes to rest on the lugs 18. The closure member D is then angularly displaced until the lugs 60 lie beneath the lugs 18 and the bolt 32 is in registry with the bore 35 in the hardened steel plug 36. The lock 20 may then be manipulated

to cause the bolt 32 to enter the bore 35 whereupon the closure member is locked in its closed position.

The construction of the lock 20 is such that two keys are required for its operation. One of the keys is retained on the premises and the other key is preferably in the possession of some company which makes daily calls to collect money deposited in the money-chest. The key retained on the premises will actuate the locking mechanism to such an extent that the bolt 32 will be retracted a short distance but not enough to withdraw it into the body portion 15 so that the body portion can be lifted from the container. When the bolt 32 is retracted by means of the key on the premises, it occupies the position wherein it is shown in Fig. 4 as distinguished from the position wherein it is shown in Fig. 5. Such partial retraction of the bolt 32 permits one to angularly displace the closure member D so that the outer end of the bolt 32 will pass from the bore 35 into an arcuate slot 62 formed in the container 10. (See Fig. 6.) It will be noted that the hardened steel bushing 36 is slotted as at 63 so that the bolt 32 may pass from the bore 35 into the slot 62. The slot 62 is of such length that it will permit the closure member to be angularly displaced from the position wherein it is shown in Fig. 5 to the position wherein it is shown in Fig. 4 so that the inclined or beveled surface 16 of the body portion 15 is aligned with the slot 13. When the closure member D is in this position, money may be inserted into the container through the slot 13. The closure member may then be returned to its closed position and the key on the premises may be used to bring the bolt 32 into its fully extended position so that it locks the closure member D against any displacement whatever relative to the container.

When the money deposited in the container 10 is to be removed therefrom, both of the keys are employed to manipulate the lock 20 so that the bolt 32 is retracted and lies entirely within the bore 34. The closure-member D may then be angularly displaced to bring the lugs 60 into the positions wherein they lie between the lugs 18 and permit the closure-member to be lifted bodily from the container.

While I have shown and described certain embodiments of my invention, it is to be understood that it is capable of many modifications. Changes, therefore in the construction and arrangement may be made without departing from the spirit and scope of the invention as disclosed in the appended claims, in which it is my intention to claim all novelty inherent in my invention as broadly as possible, in view of the prior art.

I claim:

1. A deposit-safe comprising: a container having a door-opening therein and a slot extending from said door-opening into the interior container; and a closure-member for said door-opening, said closure-member comprising a lock for locking it in said door-opening, said closure-member being adapted to be angularly displaced, while it is locked to said container, into positions wherein it covers and uncovers that end of said slot opening into said door-opening.

2. A deposit-safe comprising: a container having a door-opening therein and a slot extending from said door-opening into the interior of the container, said container being provided with lugs projecting into said door-opening; a closure-member for said door-opening, said closure-member being provided with lugs engageable with the

- lugs on said container to prevent withdrawal of said closure-member from said container, said closure-member being adapted to be angularly displaced in said door-opening to bring its lugs into 5 and out of the positions wherein they engage the lugs on the container; and means for locking said closure-member to said container, said closure-member being adapted to be angularly displaced, while it is locked in said container, into and out of 10 positions wherein it covers and uncovers, respectively, that end of the slot opening into the door-opening.
3. A deposit-safe comprising: a heavy-walled container having a door-opening therein and a slot in its wall extending into the interior thereof; a closure-member for said container adapted to be moved into and out of positions wherein it covers and uncovers the outer end of said slot while it continues to close said door-opening; and means securing said closure member in 15 said door opening while it is in a position covering said slot or in a position uncovering said slot, said securing means being adjustable to release said closure member from said container.
- 20 4. A deposit-safe comprising: a heavy-walled container having a door-opening therein and having a slot in its wall communicating with the interior of the container; a closure-member for said door-opening and adapted to be moved into a position wherein it closes said slot and into a position wherein it uncovers said slot; and means for holding said closure-member locked to said container in the door-opening thereof while it is in said positions or is being displaced from 25 one to the other, said last-mentioned means being adjustable to release said closure-member from said container to permit it to be withdrawn from said door-opening.
- 25 5. A deposit-safe comprising: a heavy-walled container having a door-opening therein and a slot in its wall extending from said door-opening to the interior of the container, said container having a plurality of spaced lugs projecting into said door-opening; a closure-member for 30 said door-opening adapted to be lifted bodily therefrom and provided with spaced lugs adapted to pass between the lugs on said container, said closure-member being adapted to be angularly displaced in said door-opening to bring its lugs beneath the lugs on said container for preventing withdrawal of the closure-member from the door-opening; a lock carried by said closure-member; a bolt controlled by said lock and adapted to engage said container to prevent said closure-member from being displaced relative to said container, said lock being adapted to partially retract said bolt to permit angular displacement of said closure-member in said door-opening while it remains locked to the container, said 35 angular movement being less than that required to bring the lugs on said closure-member out of engagement with the lugs on said container and said closure-member being adapted to uncover said slot at one end of said angular movement.
- 40 6. A deposit-safe comprising: a heavy-walled container having a door-opening therein and a money-slot in its wall extending from said door-opening to the interior of the container, said container having a plurality of spaced lugs projecting into said door-opening, the surface of 45 the door-opening having a bolt-receiving recess therein and an arcuate slot of less depth than said recess; a closure-member for said door-opening adapted to be lifted bodily therefrom and provided with spaced lugs adapted to pass be-
- tween the lugs on said container, said closure-member being adapted to be angularly displaced in said door-opening to bring its lugs beneath the lugs on said container for preventing withdrawal of the closure-member from the door-opening, 50 said closure-member being adapted to cover said money-slot when it is in one position and to uncover said money-slot when it is angularly displaced to another position; a lock carried by said closure-member; a bolt controlled by said lock and movable into a position wherein it extends into said recess a distance greater than the depth of said arcuate slot, said lock being adapted to retract said bolt into said closure-member and to displace said bolt into a partially retracted position wherein it travels in said arcuate slot, said arcuate slot being of such length that while it is engaged by said bolt the lugs on said closure-member are in functionally operative positions with respect to the lugs on said container and said closure-member remains secured to said container, said closure-member being in the position wherein it uncovers said money-slot when the bolt engages one end of said arcuate slot.
- 55 7. A deposit-safe comprising: a container having a substantially round door-opening therein and a slot extending from the surface of said door-opening through a wall of the container or into the interior thereof; a closure-member for said door-opening, said closure-member being adapted to be lifted out of said door-opening and being adapted to be angularly displaced in the plane of said door-opening, said closure-member being formed so that when it occupies one position in said door-opening it closes said slot and when it is angularly displaced from said position into another position it uncovers said slot; and means for locking said closure-member in the position wherein it closes said slot.
- 60 8. A deposit-safe comprising: a container having a substantially cylindrical door-opening therein and a slot extending from the cylindrical surface of said door-opening through a wall of the container into the interior thereof; a closure-member for said door-opening having a cylindrical surface adapted to fit snugly in said cylindrical door-opening when the closure-member is in its closed position, one side of said closure-member being beveled at the top thereof to a point below that end of the slot opening into said cylindrical surface of said door-opening and the remainder of the closure-member being of such thickness that when it is in its closed position it is adapted to close said slot, said closure-member being mounted for angular displacement in said door-opening when it is in its closed position; and means for locking said closure-member in its closed position to close said slot.
- 65 9. A deposit-safe comprising: a heavy-walled container having a door-opening therein and a slot in its wall extending into the interior thereof; a closure-member for said container adapted to be moved into and out of a position wherein it covers the outer end of said slot; and means for holding the closure-member locked to said container while it is being displaced into or out of said position.
- 70 10. A deposit-safe comprising: a heavy-walled container having a door-opening therein and a slot in its wall extending into the interior thereof; a closure-member for said container adapted to be moved into and out of a position

- wherein it covers the outer end of said slot while it continues to close said door-opening; and means for locking said closure-member against any movement from the position wherein it closes said slot.
- 5 11. A deposit safe comprising: a heavy-walled container having a door-opening therein and a closure-member for said door-opening, said container having a slot extending from its interior to outside the container, and said closure-member being adapted to be moved into and out of a position wherein it closes said slot; and means for holding the closure-member locked to said container while it is being displaced into or out of said position.
